UNITED STATES PATENT OFFICE

LEANDER N. POND, OF KINGSPORT, TENNESSEE, ASSIGNOR TO BLUE RIDGE GLASS CORPORATION, OF KINGSPORT, TENNESSEE

APPARATUS FOR ROLLING GLASS SHEETS

Application filed May 23, 1931. Serial No. 539,569.

In a prior application filed by me July 25, 1929 and serially numbered 380,947, which matured into Patent No. 1,801,689, dated April 21, 1931 I have disclosed a method of 5 and apparatus for rolling glass sheets in which a forming roll is given an initial distortion to counteract the expansion due to the heating of the roll by glass initially contacting therewith. As shown in that application, the initial distortion is due to the natural heating of a stationary roll by the accumulation of steam at the upper portion thereof.

According to the present invention I provide for chilling the lower portion of the roll by directing a jet of water thereon, such being in addition to the cooling liquid generally employed with sheet forming rolls.

For these purposes my invention consists 20 in the construction, arrangement, and combination of the several parts of which it is composed, as will be hereinafter more fully described and claimed.

Referring to the accompanying drawing, 25 in which corresponding parts are designated by corresponding marks of reference,—

Fig. 1 is a vertical section through a sheet forming pass having my invention applied thereto;

Fig. 2 is a lateral view of a roll embodying 30 the invention; and

Fig. 3 is a longitudinal section of the roll shown in Fig. 2.

The structure shown in Fig. 1 is generally 35 of the type illustrated in my aforesaid prior application and embodies an upper forming roll A, a lower forming roll B with a forming pass C between them, and a table D on which glass may be deposited. An indicator K may be provided to show the warpage 40 of the roll A.

Contained within the upper roll A is a water induction-pipe E having its end directed to one side. This pipe extends from 45 approximately the medial plane of the roll through one end of the roll and has a swivel connection F with a supply G of warping water, the construction being such that the pipe turns with the roll. In addition, the 50 roll is provided with means for circulating

water for general cooling through the hollow interior thereof, this being accomplished by the water induction-pipe H and the water reduction-pipe J.

With this device one side of the roll will 55 be cooled by the water directed thereon from the pipe E, causing a distortion of the roll. When the desired degree of distortion is obtained, the pouring is timed so that the cold portion of the roll will be the first portion 60 of the roll to contact with the glass delivered to the machine.

In carrying out my invention the amount and temperature of the general cooling water, the casting speed, the temperature of the 65 glass, and the volume of warping water will be so adjusted that the pre-warpage obtained is compensated for by the heat brought in during the casting operation.

If desired, the pipe E may not rotate with 70 the roll but in lieu thereof may be fixed.

Having thus described my invention what I claim as new and desire to secure by United States Letters patent is:

1. In a device of the character described, 75 the combination with a hollow forming roll, means for producing a general circulation of water through the roll, and supplemental means for locally chilling one side of the roll.

2. In a device of the character described 80 the combination with a continuously rotating hollow forming roll, means for producing a general circulation of water through the roll and supplemental means fixed in relation to 85 the rotation of the roll for locally chilling one side of the roll.

LEANDER N. POND.
